UNITED STATES PATENT OFFICE.

ERASTUS WOODWARD, OF SOMERVILLE, ASSIGNOR TO GEORGE W. COPELAND, OF MALDEN, MASSACHUSETTS.

TACKING-MACHINE.

SPECIFICATION forming part of Letters Patent No. 251,755, dated January 3, 1882.

Application filed September 27, 1881. (No model.)

To all whom it may concern:

Be it known that I, ERASTUS WOODWARD, of Somerville, in the county of Middlesex and State of Massachusetts, a citizen of the United States, have made a certain new and useful Improvement in Tacking-Machines, of which the following is a full, clear, and exact description, reference being had to the accompanying drawings, forming a part of this specification, in explaining its nature, in which—

Figure 1 is a side elevation of a tacking-machine containing my invention. Fig. 2 is an elevation of the opposite side of the machine from that shown in Fig. 1. Fig. 3 is a section on the line *u u u* of Fig. 1 and a front elevation of the remainder of the machine. Fig. 4 is a detail view of the driver, knife, and centering-block hereinafter described. Fig. 5 is a horizontal section on the line *x x* of Fig. 1. Fig. 6 is a horizontal section on the line *z z* of Fig. 1. Fig. 7 is a vertical section on the line *y y* of Fig. 1. Fig. 8 is a view showing the relation of the centering-block hereinafter described to the tack-driving mechanism.

This invention relates to a power-machine for feeding the "Copeland Tack-Strip," so called, or that tack-strip in which the heads of the tacks are supported and connected by a strip of flexible material, and for driving tacks therefrom, and also to means for starting and stopping the machine, which are an improvement upon those described in Patent No. 246,437, granted me, dated August 30, 1881. It embraces a novel feeding mechanism and method of operating it, the organization, in a power-machine, of feeding mechanism and tack-driving mechanism adapted to feed said Copeland tack-strip and to drive tacks therefrom, a movable nozzle, and frictional devices automatically operated to stop the revolution of the main shaft suddenly at stated intervals.

The mechanism for starting and stopping the machine is that described in the said Patent No. 246,437, and, with two exceptions, need not further be described here. The first exception is the substitution of the movable nozzle for the foot described in said patent. This nozzle is lettered *A* in the drawings, and is shown in Figs. 1, 2, and 3. It is fastened to

the sliding plate *a*, which is the same as the

sliding plate of said patent. The nozzle has at its upper end an inverted bell or cone shaped recess, *a'*, which is adapted, when the nozzle is pressed upwardly, to fit upon the bell or cone shaped projection *a''*, through which the driveway passes. This formation enables the nozzle to be centered as it is lifted and held rigidly in place during the driving of the tack. The second exception is that which relates to the application of frictional appliances to the main shaft to quickly stop its revolution after the driving of a tack. This mechanism is shown in Figs. 1 and 5; and it consists in a disk, *B*, fixed or fastened to the main shaft, and a movable disk, *B'*, which is fastened to the clutch-lever *b*, or to the driving-pulley *b'*, which corresponds to the clutch-lever and driving-pulley in said patent, by means of the connecting-arms *b''*. A washer, *b''*, may be arranged between the two disks to increase the friction, if desired. It is obvious from this construction that upon the outward movement of one member of the clutch from the other member the two disks are brought in contact and the desirable friction or braking action obtained, and that upon the moving in of the movable member of the clutch to engage with the other member the disks are separated sufficient to prevent friction between them; also, that this must result in stopping the revolution of the main shaft suddenly upon the movement of the movable member of the clutch away from the fixed member, and that upon its movement to the fixed member the main shaft may be revolved without hindrance.

I have herein described as the method of operating the machine that specified in Patent No. 246,437; but I do not desire to be understood as confining myself to that specific method of starting the machine, as I may use any other means for causing the movable member of the clutch to engage and disengage with the fixed member without departing from the spirit of this invention.

C is the frame of the machine. *C'* is its main shaft. *C''* is the driver-bar, which has bearings in the projections *c*. *C'''* is a crank connecting the main shaft with the driver-bar. *c'* is the driver-rod, which plays up and down in the driveway of the machine and the throat above it.

The main shaft, it will be observed, has, in addition to the crank for reciprocating the driver-bar aside from the clutch mechanism, only the cam-groove D in the cam-disk d. This 5 cam-groove is the same as that described in the said Patent No. 246,437, and it is utilized, additionally to the purpose therein described, for operating the feed mechanism, the cam-pin for operating the lever of the start and stop mechanism of said patent being upon the side, and the cam-pin d' for operating the feed mechanism being underneath, as represented in the drawings.

The feed mechanism varies from that heretofore described in the patents for driving the Copeland tack-strip, in that I add a centering device, whereby the tack is always located in a given position in the throat of the machine, and a pawl having three teeth actuated in a 20 peculiar way. The centering device is formed by providing the hinged block E, which is the equivalent of the block or plate described and claimed in Letters Patent No. 197,608, dated November 27, 1877, with a vertical V-shaped 25 recess, e, between the two projections e' e'', each projection having an inclined face in the direction of the feed.

The operation of this centering device in centering a tack is as follows: The feed-pawl having pushed the tack-strip forward in the operation of feeding, the first tack in the strip is fed into the throat of the machine, the block E being pressed out by the shanks of the tacks as the strip is fed forward. When the feeding 30 stops the block returns to its original position, and the second tack will be somewhere between the points e' e'' in the recess e. As the block returns to its original position it either draws the strip back a little or pushes it forward some, according to the position that the shank of the tack bears in relation to the recess, and the face of the projection which may contact with the shank of the tack, acting, on account of its shape, to move the tack either 35 forward or back, as the case may be, to the center of the recess. Of course, if the shank of the tack happens to be at the center, it will not be moved upon the inward movement of the block.

50 The feed-pawl F has three teeth, f, and it is given these movements by mechanism herein-after described in relation to the feedway f' in feeding the tack-strip and in returning to its original position: first, an inward movement to place the teeth in line with the tacks in the strip; second, a forward feeding movement, wherein one of the teeth at least engages with the shank of the tack of the strip and feeds it forward; third, an outward movement at the 55 completion of the forward feeding movement; fourth, a backward movement to its original position; or, in other words, it is a positively-actuated four-motioned feed-pawl. It is provided with three teeth, in order that the feeding of the strip may be made absolutely certain, as it is as sure as anything can be that one of the teeth at least will find the shank of

the tack in its forward movement. It has the outward movement at the end of the throw, because the forward tooth is moved into the 70 throat of the machine, and must be withdrawn therefrom before the descent of the driver-rod. I provide it with these movements by mechanism actuated by the cam D, as follows: the bell-crank lever f², pivoted at f³, bearing at the 75 end of the arm f⁴ a cam-pin, d', and connected at the end of its other arm, f⁵, by a connection which will permit of suitable adjustment with the lever f⁶ at the upper end of the rock-shaft f⁷. This shaft has a suitable bearing in the 80 frame of the machine, and carries at its lower end the lever f⁸, through which a short shaft or pivot, f⁹, extends. This shaft or pivot supports the lever f¹⁰, and also the lever or arm f¹¹, and has the extension f¹², bearing the nut f¹³, between which and the upper surface of the lever f¹¹ is the coiled spring f¹⁴. This construction clamps the levers or arms f¹⁰ f¹¹ to the lever f⁸ with sufficient friction to prevent them from turning on the lever f⁸, except one 85 of the arms comes in contact with a stationary stop. The washers f¹⁴ f¹⁵ may be interposed between the two arms and the lever f⁸, to assist in the clamping action of the said devices. The lower arm, f¹⁰, supports the pawl. The 90 operation of this mechanism is as follows:

Supposing the position of the pawl to be as represented in Fig. 6, the cam, revolving, causes the shaft f⁷ to partially revolve, thereby causing it to move the lever f⁸ sufficiently to throw 100 the inner end of the arm f¹⁰, and consequently the pawl, a distance sufficient to cause the pawl to enter the feedway. The end of the lever f¹⁰ then comes in contact with a stop, and of course prevents its further movement in that 105 direction. As, however, the revolution of the shaft f⁷ still continues, the movement of the arm f¹⁰ must be converted into a forward movement, and as it can move on the center f¹⁰ against the stress of the friction, it is caused 110 to be advanced forward, and thereby feeds the tack-strip, moving slightly on the center f¹⁶ while so doing, and the lever f⁸ also moves upon the center of the shaft f⁷. Upon the reverse movement of the lever f⁷, which occurs 115 at the end of the feed motion, the lever f⁸ first throws or moves outward the arm f¹⁰ until the arm f¹¹ comes in contact with the stop f¹⁷, when the movement is again converted from that of an arc of a circle to that of a straight movement, and the feed-pawl is returned upon that 120 line to its original position, preparatory to again feeding.

It will be observed that the lever f⁸ and its operative mechanism cause the arms f¹⁰ f¹¹ to 125 be moved upon the arc of a circle until they come in contact with stops, when the movement is changed to that of a straight line parallel with the surface of the stops, and by this means I am enabled to get the four-motioned 130 movement above referred to.

Another feature of my invention consists in attaching to the driver-rod the knife G, which reciprocates therewith through the passage g,

and which severs that portion of the tack-supporting strip from which the tacks have been driven from the remainder of the strip.

The tack-strip is fed by hand into the feed-way to a position sufficiently advanced to enable the feed-pawl to engage with the shank of the first tack therein, and is then automatically fed by the feed-pawl to the action of the driver, and the part of the strip from which the tacks have been driven is cut off as it projects beyond the end of the machine.

The advantages of the machine are in its efficiency, simplicity, and cheapness of construction.

15 Having thus fully described my invention, I claim and desire to secure by Letters Patent of the United States—

1. In a machine for driving fastenings, a nozzle provided with a vertical movement, in combination with mechanism, substantially as described, connecting it with the actuating-pulley, whereby the movement of the nozzle both starts and stops the machine, all substantially as and for the purposes set forth.

25 2. The combination of a nozzle provided with a vertical movement and the means for centering it in relation to the driveway of the machine during its upward movement, substantially as specified.

30 3. The combination of a nozzle provided with a vertical movement and the means, substantially as set forth, for maintaining it firmly in position while at its highest position and while the fastening is being driven, all substantially as described.

35 4. In a machine for driving fastenings, the combination, substantially as shown, of a movable member of the clutch mechanism, adapted to be operated as described, and a frictional device for stopping the machine, operated by said member, whereby, upon its disengagement from the other member, the friction mechanism is caused to act and the machine is stopped, and whereby, upon its engagement with said member, the friction is released, all substantially as specified.

45 5. In a machine for driving fastenings, the combination of devices, substantially as specified, for engaging and disengaging the members of the clutch mechanism and frictional mechanism, substantially as specified, adapted to be automatically operated, as described, all substantially as set forth.

6. In a machine for driving tacks from a

tack-strip, as a means for centering a tack in the throat of the machine, a yielding or movable block, E, having the centering-projections $e' e''$, forming a recess, e, and adapted to close or be closed into the feedway, all substantially as specified.

7. In a machine for driving tacks from a tack-strip, a feed-pawl arranged to feed the tack-strip having three or more teeth, as and for the purposes indicated.

8. In a machine for driving tacks from a tack-strip, the feed-pawl and means, substantially as set forth, for imparting to it closing, advancing, withdrawing, and backward movements, all substantially as specified.

9. The combination of the cam D, the pawl F, and the intermediate mechanism described for providing the pawl with the movement specified, all as set forth.

10. As a means for providing the feed-pawl with a four-motion feed, the lever f^8 , having reciprocating movements imparted to it, the arms $f^{10} f^{11}$, pivoted and clamped to said lever, substantially as specified, and stops for changing the direction of the movement of said arms, all substantially as described.

11. In a tacking-machine for driving tacks from a tack-supporting strip, the knife G, means, substantially as specified, for imparting to it a reciprocating movement, the tack-driving and tack-feeding mechanism, all arranged in relation to each other as set forth, whereby the knife is operated to sever from the tack-supporting strip the portions from which tacks have been removed, all substantially as described.

12. In an organized power-machine for driving tacks from a tack-supporting strip, the combination of the main shaft, a cam, and starting and stopping mechanism with said feed-pawl and start and stop mechanism, all substantially as specified.

13. In an organized power tacking-machine for driving tacks from a tack-supporting strip, the combination of the following instrumentalities: a driver and feed-pawl, a main shaft having a cam for operating the pawl, and a crank for operating the driver, and the means for revolving it, all substantially as specified.

ERASTUS WOODWARD.
